GAME BOARD

Frank M. Swan, Kansas City, Mo.

Application July 6, 1953, Serial No. 25,817

Term of patent 14 years

(Cl. D34—5)

To all whom it may concern:

Be it known that I, Frank M. Swan, a citizen of the United States, residing at Kansas City, in the county of Jackson and State of Missouri, have invented a new original, and ornamental Design for a Game Board, of which the following is a specification, reference being had to the accompanying drawing, forming part thereof.

The drawing is shaded to illustrate contrast of color.

I claim:

The ornamental design for a game board, as shown and described.

FRANK M. SWAN.
